UNITED STATES PATENT OFFICE.

JOSEPH SILVERMAN, OF SAN FRANCISCO, CALIFORNIA.

TELEPHONE ATTACHMENT.

No. 806,372.

Specification of Letters Patent.

Patented Dec. 5, 1905.

Application filed May 26, 1905. Serial No. 262,357.

To all whom it may concern:

Be it known that I, JOSEPH SILVERMAN, a citizen of the United States, residing in the city and county of San Francisco and State of California, have invented new and useful Improvements in Telephone Attachments, of which the following is a specification.

My invention relates to a telephone attachment, and especially to a device for holding the receiver in suitable position relative to the mouthpiece whereby both hands of the operator may be left free. Its object is to provide a simple, practical, adjustable attachment for ordinary hand and desk telephones which is adapted not only to hold the receiver, but which will automatically connect the telephone with the central station without the operator touching the hook, and which will allow the hook to remain up and maintain the connections if it is necessary to leave the phone for an instant or call some one, but which attachment is so constructed that when one has ceased talking moving the head away allows the receiver to swing back to center in front of the mouthpiece and the hook will be automatically depressed again and break the circuit.

The main objection of the telephone companies to the various receiver-holder attachments is the liability of leaving the circuit open, or the common fault of "leaving the receiver off the hook." This difficulty is obviated in my invention.

The invention consists of the parts and the construction and combination of parts, as hereinafter more fully described and claimed, and having reference to the accompanying drawings, in which—

Figure 1 is a side elevation of my device. Fig. 2 is a plan view of same.

A represents a portable base or stand provided with suitable means, as the clamp-screws 2, to receive and hold an ordinary hand-telephone, as 3. Extending upward from this base is a post 4, carrying the sliding bracket 5, in which the angular rocker member 6 is fulcrumed. This rocker member has a portion 6' to bear on the ordinary telephone-hook 7, which in telephones usually provided with my attachment usually supports the receiver. A spring 8, connected to the bracket 5 and to the rock-arm or depressor 6', tends to pull the arm and hook down, so as to close the circuit between the two electrodes 9 10, which are connected with the terminals of the transmission portion of

the apparatus. The pivot portion of the member 6 carries a projecting pin 11, which normally engages in the crotch of a double or symmetrically-forked cam member 12, which is carried by a sleeve 13, and which sleeve rests on the bracket 5 and is free to turn in either direction on the post 4.

The bracket 5 is shown as bifurcated and the pin 11 as having a tubular portion or collar 11^a disposed between the forks of the bracket and embracing the corresponding part of member 6. The collar and pin are locked to member 6 by a set-screw 14. This construction enables the depressor 6' to be shifted to vary the leverage on the telephone-hook or to vary the oscillating movement of depressor.

The sleeve 13 carries an extendible lateral arm 15, the outer member of which has a segment or plate 16 at its outer end arranged in a vertical plane. A small block 17 is mounted to turn on one side of 16, and an arm 18 is pivoted to a block 17 to turn at right angles to plate 16. Arm 18 has a pin 19 on its inner side arranged to engage any one of a series of perforations 20 disposed in an arc concentric with the pivot of block 17. A spring 21, secured to block 17, bears on arm 18 and tends always to press the latter in against plate 16 and force the pin 19 into a hole 20. The purpose of this perforated plate and hinged arm 18 is to adjust the receiver 22, which is carried by arm 18, to just the right elevation suited to the user of the telephone, while the extendible arm 15 allows the receiver to be moved out or in the proper distance relative to the mouthpiece.

The arm 18 carries a hinged block 23 at its outer end arranged to swing in a vertical plane. The outer end of this block is radially grooved, as shown at 24, and a plate 25, having corresponding projections 26 on its under side, is held against the end of block 23 by the screw 27 and spring 28. The tension of this spring is such that the plate 26 will always be pressed hard against block 23, and the engagement of the projection 26 with a groove 24 will keep the plate and the receiver 22 from turning when once adjusted to the right inclination. The receiver is held by suitable means, as the spring-clamping device 29, carried by plate 26.

Usually the parts are so arranged and adjusted that when the telephone is not in use the arms 15 18 will stand in a vertical plane above the mouthpiece 30.

The cam member 12 is made forked in the manner shown, and each fork is so curved outward and oppositely that while the pin 11 will ordinarily rest in the crotch between the 5 forks, as before stated, and allow spring 8 to act on the depressor to hold the hook down, a suitable movement of the receiver and its holding means to one side or the other of the mouthpiece will cause one or the other of the 10 forks of the cam to rock the pin 11 and allow the hook to lift, thereby connecting the telephone with central station. The cam branches are made suitably eccentric, so that if the receiver-holding arm is swung far 15 enough in either direction the pin will be carried onto a flatter portion, as 12^a, of a cam to enable the operator to move away from the telephone or call some one without the hook being depressed and the connection broken, 20 as would be the case if the receiver-arm swung back to center. With the pin 11, however, at any point intermediate the crotch of the cam and the surfaces 12^a the spring 8 will operate through the depressor, pin 11, and 25 the cam-surfaces to bring the receiver-arm to center and depress the hook. Another important thing in this connection is that it takes such a long movement, comparatively, of the receiver to one side of the 30 mouthpiece to carry the pin onto a surface 12^a, where the hook is allowed to stay up without pressure being maintained on the receiver, that one would never under ordinary circumstances leave the hook up after 35 talking through the telephone, since it only takes a movement of the receiver of a couple of inches to one side or the other of the mouthpiece to lift the hook and to bring the lips opposite the mouthpiece with the receiver 40 against the ear. The lifting of the hook and the connecting with central is simply done by placing the ear against the receiver and moving the head a little to one side to bring the speaker's lips opposite the 45 mouthpiece. When through talking, moving the head away allows the receiver to swing back to center in front of the mouthpiece, and the hook is automatically depressed and the circuit broken. The receiver 50 needs never to be taken from its clamp 29. No matter how forgetful or absent-minded one may be the moment the user leaves the phone, in case of course the receiver-arm is not deliberately swung away to 55 one side to cause the pin to ride onto a part 12^a, the circuit is broken and there can be no such complaint as is the equivalent now of the receiver being "off the hook."

The attachment is applicable to any ordinary hand-telephone or wall-telephone having a hook to make and break the circuit.

It is possible that various modifications in my invention may be made without departing from the principle thereof, and I do not 65 wish to be understood as limiting myself to

the specific construction as herein shown and described.

Having thus described my invention, what I claim, and desire to secure by Letters Patent, is—

1. The combination with a telephone hook and mouthpiece, of a suitably-supported depressor for the hook, a receiver-holder having a movement laterally of the mouthpiece, and means including a member operated by 75 the receiver-holder and having a crotch with symmetrical cam portions at each side thereof of said depressor having a member normally engaging the crotch of said member and actuated by the cam portions thereof which- 80 ever way the receiver-holder is oscillated.

2. The combination with a hook and mouthpiece of a telephone, of a suitably-supported receiver-holder having a movement laterally of the mouthpiece, a hook-de- 85 pressor and means actuated coördinately with the receiver-holder to operate the depressor said means including a member having a crotch engaged by the hook-depresser and having, also, cam portions at each side 90 of the crotch whereby the depressor is actuated whichever way the receiver-holder is oscillated.

3. The combination with a telephone having a mouthpiece and a hook, of a hook-de- 95 pressor, an adjustable, extendible swinging receiver-holder, and a member movable with the holder and having a central crotch in which the depressor normally engages, said member having cam portions at each side of 100 the crotch whereby the depressor is actuated whichever way the receiver-holder is oscillated.

4. The combination with the hook and mouthpiece of a telephone, of a hinged depressor, a hinged receiver-holder, a forked cam operated by the receiver-holder, and means carried by the depressor engageable with said cam, whereby the depressor is actuated 105 whichever way the receiver-holder is 110 oscillated.

5. The combination with the hook and mouthpiece of a telephone, of an oscillating depressor for the hook, a receiver-holder mounted to swing from side to side of the 115 mouthpiece, a forked cam operable by the receiver-holder engaging a part on the depressor, and means for maintaining said part normally in the crotch of said cam.

6. The combination with the mouthpiece and hook of a telephone, of a receiver-holder having a movement laterally of the mouthpiece, means for actuating the hook and means including a cam having a flattened seat for the hook-actuating means said cam tending to maintain the receiver-holder in a fixed normal position with the hook depressed.

7. The combination with the mouthpiece and hook of a telephone, of a vertical post, a 130

bracket carried by said post, a depressor for the hook pivoted on said bracket, a sleeve member turnable on said post, a cam carried by said sleeve member and engaging a part 5 on the depressor to actuate the latter, and a receiver-holder carried by said sleeve.

8. In a telephone attachment, an extendible arm formed of telescopic sections said arm mounted to swing from side to side of 10 the mouthpiece, one of said sections having a perforated plate at its outer end, a spring-pressed member pivoted on said plate and adapted to be moved in a vertical plane, and having a projection engageable with said 15 perforations to hold said member at different inclinations relative to said arm, and means carried by said member for holding a receiver.

9. In a telephone attachment, an arm 20 mounted to swing from side to side, said arm comprising sections capable of sliding one relative to the other, a plate carried by one of said sections and arranged in a vertical plane, a second arm pivoted on said plate and 25 adapted to form an extension of the arm and having a projection engageable with perfor-

ations in said plate, whereby said second arm may be held by different inclinations relative to the first, and means on second arm for holding a receiver. 30

10. In a telephone attachment, the combination with a hinged arm, of means carried by said arm for supporting a receiver, said means including a part connected with the arm having a radially-corrugated end, a 35 plate swiveled coaxially with relation to said radial corrugations, a projection carried by the said plate engageable with the corrugations, and means including a screw passing through one of said plates and threaded into the other plate, and a spring engaged by the screw for constantly pressing said plate against said corrugated surface to hold the plate in position. 40

In testimony whereof I have hereunto set 45 my hand in presence of two subscribing witnesses.

JOSEPH SILVERMAN.
